UNITED STATES PATENT OFFICE.

HARRY RUST, OF NORTH JUDSON, INDIANA.

RAILROAD-CROSSING.

1,195,402.

Specification of Letters Patent. Patented Aug. 22, 1916.

Application filed June 3, 1916. Serial No. 101,530.

To all whom it may concern:

Be it known that I, HARRY RUST, a citizen of the United States, residing at North Judson, in the county of Starke and State of Indiana, have invented certain new and useful Improvements in Railroad-Crossings, of which the following is a specification, reference being had to the accompanying drawings.

10 This invention relates to the construction of road beds, and particularly to the construction used where a road crosses a railroad track. It is usual at this point to fill in the spaces between the tracks and on each side of the tracks with boards or planks spiked in place, the planks being raised to an approximate level with the top of the rail.

20 The general object of my invention is to do away with the use of planks under these circumstances, and provide a sheet metal structure composed of units which may be readily put in place on each side of a rail and spiked to the cross tie, these units being 25 identical in length and being of such length that they may be combined to provide an eighteen foot, twenty-four foot, or longer crossing, if it is necessary.

In the accompanying drawings, Figure 1 30 is a cross sectional view of a crossing showing my beam applied to the road-bed; Fig. 2 is a fragmentary top plan view of a portion of a railway track with my crossing members applied thereto; Fig. 3 is a side elevation of the structure shown in Figs. 1 and 2; Fig. 4 is an end elevation of the structure, the rails being in cross section; and Fig. 5 is a perspective view of one of the end plates 25.

40 I have illustrated my construction as applied to standard rails mounted on ordinary ties but it may be applied, of course, to rails of any desired height or weight.

In the drawings, 10 designates the ties of 45 the track and 11 the rails thereof, a double track being illustrated in Fig. 1. On the outside of each rail there is disposed a hollow casing or box designated generally 12, comprising a beam 13, a side plate 14 which 50 is inclined downward and outward, this side plate at its upper end being angularly bent as at 15 to provide a web extending across the top of the beam 13 and riveted or otherwise firmly attached thereto. This web 55 15 may be of any desired width. Inasmuch as the rail is approximately five and three-

quarter inches high, the beam 13 is approximately five and three-quarter inches high. The web 15 is attached at its middle to the beam 13 and the outer edge of the plate 14 60 is formed with a flange 16 forming a foot, which flange is about two inches wide and is spiked to the tie. On the inside of each rail of a pair of rails, is a box designated 17, which is also composed of a longitudinally 65 extending beam 18, this beam, however, not being flanged at its upper end. There is a side plate 19 flanged at its lower end and spiked to the tie, this plate 19 extending upward and inward to a height equal to the 70 height of the beam 18 and then extending horizontally, as at 20, over the edge of the beam 18, then being bent vertically downward, as at 21, and then laterally, as at 22, and engaging with the rail 11 immediately 75 beneath the head thereof. The width of the portion 19 is about the same as the portion 15. Each of these boxes 12 and 17 are preferably made about six feet long. These boxes form a plurality of hollow metallic 80 shells, which may be abutted against each other, as described and which may extend along the tracks for any desired distance by using a greater or less number of boxes or shells.

85 It will be seen that a space is left between each pair of rails which extends downward to the tie. This space is intended to be filled with concrete 24, ballast or other suitable material, as for instance earth or cinders and this material is held in place by the end pieces 25, which end pieces are downwardly and outwardly inclined, as illustrated most clearly in Fig. 5 and have downwardly extending vertical webs 26. The lower end of each plate 25 is formed with a flange 27 whereby it may be spiked to a tie. End plates of the same character are attached to the ends of the boxing 12, these end plates being designated 25^a. Lake plates, designated 25^b are attached to the ends of the boxings and extend between the double tracks or between triple tracks, this space between the double tracks being intended to be filled with concrete or other like material 90 24^a. The beams 13 might be formed integral with the plate 14 and 15 and the beams 18 might be formed integral with the plate 20, 21 and 22. I do not wish to limit myself to any particular manner of forming these 95 100 boxes 12 and 17.

105 My invention provides for a very perma-

uent crossing and one which will not wear out and be readily damaged as is the case with the ordinary plank crossing in use today. This crossing structure may be read-
5 ily and cheaply manufactured, and as the sheet metal is relatively light the units will weigh very little so that they may be easily transported and put in place. It requires no skilled labor to put them in place and the
10 shells or boxes may either be set up in a factory or the parts thereof shipped to the place where they are to be used and then bolted together.

Having described the invention, what is
15 claimed is:—

1. A crossing structure for railway tracks including sheet metal boxes or shells disposed on each side of each rail of the track and spiked to the ties, the top walls of the
20 boxes being level with the top of the track, said boxes including longitudinally extending vertically disposed supporting members resting upon the ties and disposed inward of the inner edges of the boxes, the inner edges of said boxes being separated from
25 the rails.

2. A crossing structure for railway tracks including sheet metal boxes or shells disposed on each side of each rail of the track and spiked to the ties, said sheet metal boxes being formed in longitudinal sections, the sections being abutted against each other, the top walls of the boxes being level with
30

the top of the track, longitudinally extending beams forming part of the boxes and supporting the same, end plates disposed between each pair of rails and abutted against the adjacent ends of the boxes, and a filling disposed between the end plates and between the adjacent boxes.
35

3. A crossing structure for railway tracks including beams disposed parallel to and outward of the rails in the track, outer upwardly inclined plates attached at their outer edges to the ties and extending over tops of the beams and attached thereto and extending nearly to the rails, parallel longitudinally extending beams disposed inward of the rails, plates spiked to the ties inward of the beams, and extending upward, then horizontally and attached to the upper ends of the beams, then extending downward and laterally to a point beneath the head of the respective rails to thereby provide a flange space, end plates attached to said boxes so 50 formed and extending downward and outward, and filling disposed below the roadbed and extending upward to the tops of the boxes.
40

In testimony whereof I hereunto affix my 55 signature in the presence of two witnesses.

HARRY RUST.
